(57) **CLAIM**

The ornamental design for a paint stacking device, as shown and described.

DESCRIPTION

FIG. 1 is a top perspective view of a paint stacking device.

FIG. 2 is a bottom perspective view thereof.

FIG. 3 is a front side elevation view thereof.

FIG. 4 is a left side elevation view thereof.

FIG. 5 is a top plan view thereof; and,

FIG. 6 is a bottom plan view thereof.

The right side is a mirror image to the left side, and the back side is a mirror image to the front side.

In the drawings, the broken lines are for the purposes of illustrating environment only and form no part of the claimed design.

1 Claim, 3 Drawing Sheets
